PHOSPHINE BORANE COMPOUNDS AND THEIR PREPARATION

Roger A. Baldwin, Robert M. Washburn, and Kendrick R. Eilar, Whittier, Calif., assignors to American Potash & Chemical Corporation, a corporation of Delaware
No Drawing. Filed June 20, 1960, Ser. No. 37,084
29 Claims. (Cl. 260—606.5)

This invention relates to a new class of phosphine boranes useful as preignition control additives for gasoline. It is an object of this invention to provide a new class of phosphine boranes which are especially suited as preignition control additives in gasoline containing tetraalkyl lead compounds, or equivalents, and which may contain ethylene dichloride and dibromide (in the case of automotive fuels) and ethylene dibromide alone (in the case of aviation fuels).

It is a further object of this invention to provide a new process for the preparation of phosphine boranes which are particularly useful as preignition additives for gasoline.

Ancillary objects and advantages of this invention, if not specifically set forth, will become apparent in the course of the description which follows.

Broadly, this invention concerns phosphine boranes of the general formula $R_{3-n}Ar_nP: BH_3$ where R represents an alkyl, cycloalkyl or aralkyl group, where Ar is an aromatic group such as, for example, phenyl, lower alkyl-substituted phenyl, halo-substituted phenyl, naphthyl and methoxyphenyl and n has a value of 1, 2 or 3.

These materials may be added to unleaded gasoline or gasoline which contains TEL or similar metal-containing anti-detonant such as methylcyclopentadienyl manganese tricarbonyl, and serve as excellent preignition additives therein, as set forth in co-pending application Serial No. 796,223, filed March 2, 1959.

When the phosphine boranes of this invention are added to motor fuel, the resultant motor fuel is found to have a low preignition index and a high resistance to detonation knocking. Another effect of the use of these phosphine boranes is to decrease the tendency of the presence of TEL, or equivalent, in the gasoline to raise the octane requirement of the engine in which the gasoline is used. A further advantage of these phosphine boranes as gasoline additives is that such phosphine boranes are highly resistant to hydrolysis, as the result of which they have little tendency to be leached from the fuel by the action of such free water as may be present. In this respect, the phosphine boranes as a class are decidedly advantageous as compared with most other boron-containing gasoline additives which are highly vulnerable, in most instances, to hydrolysis.

The phosphine boranes of this invention are also superior to the closely related compounds $Ar_3P: BX_3$ and $R_2ArP: BBr_3$ of the prior art in that they are generally liquids or low melting solids, have a much higher solubility in gasoline, and are considerably more stable than the most closely related compounds described in the prior art. For example, the compounds of the present invention, when tested for hydrolytic stability by shaking with water (as found at the bottoms of gasoline storage tanks), were found to be considerably more stable than compounds such as

$(CH_3)_3P: BBr_3$; $(C_4H_9)_3P: BBr_3$; $(C_6H_5)_3P: BCl_3$

and $C_6H_5(CH_3)_2P: BBr_3$.

2

The particular physical and chemical properties of the phosphine boranes of the present invention are especially important in a gasoline additive since additives which have low solubilities have a strong tendency to precipitate and form solid deposits when the fuel mixture is vaporized in the carburetor. It is desirable, but not essential, that the phosphine boranes be low-melting materials, since this property also reduces the tendency of the additives to precipitate and form the aforementioned solid deposits.

Such deposits cause malfunctioning of the engine in addition to defeating the purpose of feeding the additive into the combustion chamber. Liquids are also desirable from a material-handling standpoint since they may be blended conveniently with liquid fuels.

Also, it is self-evident that if the compounds are to be used as gasoline additives, they must be sufficiently soluble in the hydrocarbon fuel material to provide the desired results. For example, for a standard leaded gasoline containing 3 ml. per gallon of tetraethyl lead, it is necessary that the phosphorus-containing additive be present at 0.3 theory, which represents 3.07 g.-atoms of P per gallon or 0.81 g.-atoms of P per liter.

The phosphine boranes of the present invention, while sufficiently soluble in hydrocarbons, are relatively insoluble in water and this also tends to maintain quantitative requirements at low levels since there is essentially no loss by extraction.

Various methods are available for preparing the starting phosphines. (See Kosolapoff, "Organophosphorus Compounds," John Wiley and Sons, New York, 1950.) For example, the following equations outline the procedures followed for the preparation of the starting phosphines.

Several preparative methods can be used for preparing the phosphine boranes described herein; for example, the phosphonium halide can be caused to react with a metal borohydride as typified by Equation 4.

Although this process has the advantage that diborane does not have to be handled as shown in Equation 5, it has the disadvantage of being inefficient in consuming a mole of hydrogen halide and the loss of a B—H bond through formation of hydrogen.

A second general process involves the reaction of the phosphine with diborane as typified by Equation 5.

Although this process is more efficient than the process shown by Equation 4, it suffers by the disadvantage that the toxic, flammable, and explosive diborane is used.

There has been found a new general process for the preparation of phosphine borane which obviates the disadvantages of the processes represented by Equations 4 and 5. This new general process involves the reaction of an amine borane with the phosphine as shown in Equation 6.

where R' is alkyl or aryl, at least two of the groups R'

representing alkyl, or in the alternative, where two or all three R' groups together represent a single divalent radical joined to the nitrogen to form a heterocyclic ring with any remaining R' group representing lower alkyl, e.g., pyridine, a lower alkyl-substituted pyridine or N-methyl-piperidine and where R, Ar and n are as defined above. The amine borane employed is not critical; typical examples are trimethylamine borane; triethylamine borane; tripropylamine borane; tributylamine borane; dimethyl-ethylamine borane; butyldimethylamine borane; phenyl-dimethylamine borane; N-methylpiperidine borane; pyridine borane; 2-methylpyridine borane; 3-methylpyridine borane; or 4-methylpyridine borane. Amine boranes having two aryl groups cannot be prepared but any of the amine boranes which may be formed work satisfactorily.

This process also has the additional advantage that it can be simply adapted to a continuous process for the preparation of the phosphine boranes. For example, the reaction of the amine borane and the phosphine proceeds slowly at room temperature, but becomes rapid at higher temperatures. Therefore, a mixture of the amine borane and the phosphine can be fed to a center-feed column maintained at a convenient temperature (by application of vacuum), and the amine removed as distillate from the top of the column, and the phosphine borane removed as product from the bottom of the column.

Specific examples are set forth below showing the preparation of the phosphine boranes of this invention, but these are for illustrative purposes only and are not to be interpreted as imposing limitations on the scope of the invention other than as set forth in the appended claims.

EXAMPLE I

Preparation of Phenyldimethylphosphine Borane

A 13.8 g. (0.1 mole) quantity of phenyldimethylphosphine was mixed, under argon, with 11.5 g. (0.1 mole) of triethylamine borane. The mixture was heated and triethylamine, B.P. 88-90° C., was removed by distillation. After approximately two-thirds of the amine had been distilled at atmospheric pressure from the mixture, the remainder was removed at reduced pressure. The residue was then distilled, yielding 10.7 g. (0.07 mole, 70.4%) of a colorless liquid, B.P. 85-88° C. at 0.5 mm., n_{D}^{21} 1.5504.

Analysis.—Calcd. for $C_8H_{14}BP$: B, 7.12; P, 20.38; 45 B/P, 1.00. Found: B, 7.07; P, 20.3; B/P, 0.995.

EXAMPLE II

Preparation of 2,5-Dimethylphenyl-Di-n-Butyl-Phosphine Borane

Using the same reaction conditions as described in Example I, 2,5-dimethylphenyl-di-n-butyl-phosphine borane was prepared in 83.3% yield; B.P. 140-141° C./0.5 mm.

Analysis.—Calcd. for $C_{16}H_{30}BP$: B, 4.10; P, 11.72; B/P=1.00. Found: B, 4.08; P, 11.7; B/P=1.001.

EXAMPLE III

Preparation of Mixed m- and p-Ethylphenyl-dimethylphosphine Borane

Using the same procedure and reaction conditions as described in Example I, mixed m- and p-ethylphenyldimethylphosphine borane was prepared in quantitative yield; B.P. 89-92° C./0.3 mm.

Analysis.—Calcd. for $C_{10}H_{18}BP$: B, 6.01; P, 17.21; B/P=1.00. Found: B, 5.81; P, 17.22; B/P=0.966.

EXAMPLE IV

Preparation of Triphenylphosphine Borane

Using the same general procedure used in Examples I-III, triphenylphosphine borane was prepared in 83.3% yield; M.P. 182-184° C.

Analysis.—Calcd. for $C_{18}H_{18}BP$: B, 3.92; P, 11.22; B/P=1.00. Found: B, 3.67; P, 11.22; B/P=0.936.

Following the methods set forth above, various other materials may be prepared in like fashions; e.g., see the table below which designates the starting phosphine and the phosphine borane product, triethylamine borane being used as the second reactant in each case.

	Phosphine	Phosphine borane
10	(C_6H_5) ₂ P(CH_3) ₂	(C_6H_5) ₂ P(CH_3) ₂ : BH_3
	(p - CH_3 - C_6H_4) ₂ P(CH_3) ₂	p - CH_3 - C_6H_4 (C_6H_5) ₂ : BH_3
	2,5-(CH_3) ₂ CoH ₄ P(CH_3) ₂	2,5-(CH_3) ₂ CoH ₄ P(CH_3) ₂ : BH_3
	p -Cl— C_6H_4 P(C_6H_5) ₂	p -Cl— C_6H_4 (C_6H_5) ₂ : BH_3
	p -Br— C_6H_4 P(C_6H_5) ₂	p -Br— C_6H_4 (C_6H_5) ₂ : BH_3
	p (CH_3O) ₂ C_6H_4 P(CH_3) ₂	C_6H_5 (p - CH_3O) ₂ C_6H_4 P(CH_3) ₂ : BH_3
	p (CH_3O) ₂ C_6H_4 P(CH_3) ₂	p (CH_3O) ₂ C_6H_4 P(CH_3) ₂ : BH_3

	(p - Br C_6H_4) ₂ P	(p - Br C_6H_4) ₂ P: BH_3
	(p - CH_3O C_6H_4) ₂ P	(p - CH_3O C_6H_4) ₂ P: BH_3
	C_6H_5 P(CH_2 C_6H_5) ₂	C_6H_5 P(CH_2 C_6H_5) ₂ : BH_3

As aforementioned, a test for preignition has been devised and the new compounds of this invention have been compared with other closely related compounds, as 20 a result of which the superiority of these compounds has been made apparent. Briefly, this test involves measuring the number of instances per unit time of motor operation in which flames occur in the combustion chamber prior to the time at which the normal flames produced by 25 the spark occur, in general following the procedure described by Hirschler, McCullough and Hall, SAE Trans., 62, 40 (1954). Efficiency of the preignition additive can be measured by the preignition index, which is a percentage of such abnormal flames occurring in the additive-containing test gasoline as compared with the base fuel, i.e., the same TEL-containing gasoline which has not 30 been treated with the preignition additive.

Obviously, many modifications and variations of the invention may be made without departing from the spirit 35 and scope thereof, and therefore only such limitations should be imposed as are indicated in the appended claims.

In the formulae used heretofore and used in the claims hereinafter, the symbol R indicates an aliphatic radical 40 having 1-12 carbon atoms such as methyl, ethyl, cyclohexyl, and octyl. Ar represents an aromatic or substituted aromatic radical such as phenyl, chlorophenyl, alkoxypyphenyl, halogen substituted phenyl and naphthyl.

We claim:

1. Compounds of the general formula $R_{3-n}Ar_nP: BH_3$ wherein R represents a group selected from the class consisting of alkyl, aralkyl and cycloalkyl; Ar represents a group selected from the class consisting of phenyl, lower alkyl-substituted phenyl, halo-substituted phenyl, naphthyl and methoxyphenyl and n is 1-3.
2. Compounds of claim 1 wherein R is lower alkyl.
3. Compounds of claim 1 wherein Ar is phenyl.
4. Compounds of claim 1 wherein Ar is lower alkyl-substituted phenyl.
5. Compounds of claim 1 wherein Ar is halo-substituted phenyl.
6. Compounds of claim 1 wherein Ar is naphthyl.
7. The compound phenyldimethylphosphine borane.
8. The compound 2,5-dimethylphenyl-di-n-butyl-phosphine borane.
9. The compound ethylphenyldimethylphosphine borane.
10. The compound triphenylphosphine borane.
11. The compound tri(p -methylphenyl)phosphine borane.
12. The compound naphthyl-diethylphosphine borane.
13. The compound bis(methoxyphenyl)propylphosphine borane.
14. The compound p -chlorophenyl-di-hexylphosphine borane.
15. A process for the preparation of a phosphine borane of the general formula $R_{3-n}Ar_nP: BH_3$ wherein R represents a group selected from the class consisting of alkyl, aralkyl, and cycloalkyl, Ar represents a group selected from the class consisting of phenyl, lower alkyl-

substituted phenyl, halo-substituted phenyl, naphthyl and methoxyphenyl and n is 1-3 comprising: reacting a phosphine of the general formula $R_{3-n}Ar_nP$ with an amine borane of the general formula $R'_3N:BH_3$ wherein symbols R , Ar and n are used as previously designated and wherein R' is selected from the class consisting of three separate groups, each of said groups being selected from the class consisting of (a) alkyl and aryl, at least two of said groups being alkyl; (b) two separate groups, one of which is lower alkyl and the other of which is an alkylenic group bonded at either end to nitrogen; and (c) a single heterocyclic ring which, with nitrogen, forms a heterocyclic ring selected from the class consisting of pyridine and lower alkyl-substituted pyridines.

16. The process of claim 15 wherein R' is lower alkyl.
17. The process of claim 15 wherein R is lower alkyl.
18. The process of claim 15 wherein Ar is phenyl.
19. The process of claim 15 wherein Ar is lower alkyl-substituted phenyl.
20. The process of claim 15 wherein Ar is halo-substituted phenyl.

21. The process of claim 15 wherein Ar is naphthyl.
22. The process of claim 15 wherein Ar is phenyl, wherein R is methyl and wherein n is one.
23. The process of claim 15 wherein Ar is 2,5-dimethylphenyl, wherein R is butyl and wherein n is one.
24. The process of claim 15 wherein Ar is p-ethylphenyl, wherein R is methyl and wherein n is one.
25. The process of claim 15 wherein Ar is phenyl and wherein n is three.
- 10 26. The process of claim 15 wherein Ar is p-methylphenyl and wherein n is three.
27. The process of claim 15 wherein Ar is naphthyl, wherein R is ethyl and wherein n is one.
- 15 28. The process of claim 15 wherein Ar is methoxyphenyl, wherein R is propyl and wherein n is two.
29. The process of claim 15 wherein Ar is p-chlorophenyl, wherein R is hexyl and wherein n is two.
